UNITED STATES PATENT OFFICE.

FRANK HENRY EVE AND WILLIAM JAMES WOOD, OF LUTON, ENGLAND.

HAT-POLISHING AND LIKE MACHINE.

Application filed February 11, 1925. Serial No. 8,450.

This invention relates to machines of the type employed for polishing or velouring felt hats or for effecting similar finishing operations on hat bodies. Machines of this 5 class comprise a rotary "brushing-member" and a rocker arm pivoted near one end for swinging movement (usually by pedal-operated means) towards and away from the brushing-member, and provided at its free 10 end with a resilient pad for pressing the hat body into contact with the working surface of the brushing-member. The brushing-member may take various forms according to the particular operations for which it is 15 to be used; for instance it may be a felt "bob" for polishing or a carding member for velouring.

The present invention provides in a machine of the class specified above the combination with the aforesaid rotary brushing-member of a pivoted lever, a bow-shaped arm secured at one end to said lever and having its free end located in proximity to the brushing-member aforesaid, means operable at will to rock the lever aforesaid about its pivot in a direction to move the free end of the arm towards and away from the brushing-member, a pressure-applying pad carried on the free end of the bow-shaped arm, means to permit of the angular adjustment of said arm in relation to the lever about an axis which passes substantially centrally through the pad and across the arc of the arm to the point of connection between the arm and the lever, and means to lock the arm to the lever in any desired position of angular adjustment.

Preferably the pressure-applying pad is so mounted on the free end of the bow-shaped arm as to be angularly adjustable about the aforesaid axis round which the arm as a whole is adjustable.

According to a further feature of the invention a pivoted pedal is coupled by a link to the aforesaid lever to which the pad-carrying arm is attached, and means are provided to permit of adjustment in length of the coupling link, thereby enabling the pad to be adjusted towards and away from the brushing-member.

The foregoing and other features of this invention will now be particularly de-

scribed with reference to the accompanying drawings in which—

Figure 1 is an end elevation of a hat 55 polishing machine embodying the various features of the invention;

Figure 2 is a front elevation of a portion of this machine, and

Figure 3 is a view illustrating a detail. 60

Like reference numerals indicate like parts in all figures.

A rotary brushing-member 5 mounted on a spindle 6 is supported by the machine frame 7 for rotation about a horizontal axis. 65 The brushing-member 5 may be a felt bob for polishing, or it may be formed, for example, as a carding member for other finishing operations on the hat body. Operable in conjunction with the brushing-member 5 the 70 machine provides a bow-shaped arm 8, at the upper and free end of which a resilient pressure-applying pad 9 is carried. The bow-shaped arm 8 is attached at its lower end to one arm of a lever 10 which is fulcrumed on a rod 15 for swinging movement about a horizontal axis. The other arm of the lever 10 is operatively connected to a pedal lever 11 which is pivotally mounted at 32 on the machine frame. The connection 80 between the levers 10 and 11 takes the form of a screw-threaded rod 12 opposite ends of which are screwed respectively right- and left-handed. The ends of the rod 12 are engaged by internally screw-threaded sleeves 85 13, 14, the former being pivotally connected to the lever 10 and the latter similarly connected to the pedal lever 11.

It will be seen that by depressing the pedal lever 11 the lever 10 is rocked about its axis 90 in a direction to move the pad 9 towards the periphery of the brushing-member 5, similarly if the pedal 11 be raised the pad 9 will be drawn away from the brushing-member. The pedal lever 11 and associated 95 parts (which by their weight exert a leverage in the clockwise direction about the fulcrum 15) are so weighted in relation to the weight of the bow-shaped arm 8 and its associated parts (which by their weight exert 100 a leverage in the counter clockwise direction about the fulcrum 15) that the tendency to rotate the lever 10 in one direction about its axis is balanced by the tendency towards

rotation in the opposite direction. The parts are shown in their normal, that is balanced positions in Figure 1. A compression spring 16 is located below the pedal lever 11 and operates to resist downward movement of said lever. Thus when the pedal is depressed to bring the pad 9 up to the brushing-member there is a resilient force tending to bring the parts back to their normal positions.

The adjustable connection between the levers 10 and 11 enables the operator to vary the gap which normally exists between the pad 9 and the periphery of the brushing-member. To effect such a variation it is only necessary to turn the screw-threaded rod 12 in one or other direction and when the necessary adjustment has been made, to lock the rod against further turning movement; for this purpose a lock nut 17 is provided. The extensible connecting link between the levers 10 and 11 thus allows of the pad 9 being moved towards the brushing member 5 in order to make up for wear in the latter.

The pad supporting arm 8 is bow-shaped in order to provide the necessary clearance for the hat body when the latter is passed over the pad 9. When operating on certain portions of the hat body additional clearance is desirable and for this purpose the invention provides means to permit of the angular adjustment of the arm about an axis 18 which passes from end to end of the arm across the arc of the bow. The lower end of the arm 8 is secured to the lever 10 by a screw 19 the centre line of which is coincident with the aforesaid axis 18. After the arm 8 has been adjusted to the required angular position it may be locked firmly to the lever 10 by means of a lock nut 30. The pad 9 is secured to the upper end of the arm 8 by a screw 20, the centre line of which is also coincident with the aforesaid axis 18. When the arm 8 has been swung through say 90° from the position illustrated in Figure 1, it is necessary in order to bring the pad 9 square with the working surface of the brushing-member, to move the pad in relation to the arm through a similar angle. When the pad has been thus adjusted it is secured in its new position by a lock nut 21. It will be seen that with this arrangement the bow-shaped arm 8 may be adjusted to any desired angular position, the pad 9 being in each case brought back to the same position in relation to the working surface of the brushing-member.

The pad 9 in addition to being adjustable about the axis 18 is also adjustable about an axis at right-angles thereto. Figure 3 shows clearly the method by which the pad is secured to the upper end of the screw 20. Co-operating ratchet teeth 22 are formed on the two parts and adjustment of the one rela-

tively to the other takes place about the axis of a clamping screw 23. The above arrangement allows of the pad being adjusted to contact with the brushing-member at different levels.

What we claim as our invention and desire to secure by Letters Patent is:

1. In a hat polishing or like machine of the class specified the combination with a rotary brushing member of a pivoted lever, a bow-shaped arm secured at one end to said lever and having its free end located in proximity to the brushing member aforesaid, means operable at will to rock the lever aforesaid about its pivot in a direction to move the free end of the arm towards and away from the brushing member, means to permit of the adjustment of the arm on the lever angularly about an axis which passes through the point of connection of the arm and the lever and through the extremity of the free end of the arm; a pressure-applying pad mounted on said free end of the arm, means to permit of the adjustment of said pad on the arm about the aforesaid axis round which the arm as a whole is angularly adjustable, and means to lock the arm to the lever and the pad to the arm in any desired positions of adjustment.

2. In a hat polishing or like machine of the class specified the combination with the rotary brushing member of a pivoted lever, a bow-shaped arm secured at one end to said lever and having its free end located in proximity to the brushing member aforesaid, means operable at will to rock the lever aforesaid about its pivot in a direction to move the free end of the arm towards and away from the brushing member, means to permit of the adjustment of the arm on the lever angularly about an axis which passes through the point of connection of the arm and the lever and through the extremity of the free end of the arm; a pressure-applying pad mounted on said free end of the arm, means to permit of the adjustment of said pad on the arm about the aforesaid axis around which the arm as a whole is angularly adjustable and also about an axis at right angles to that round which the arm as a whole is adjustable, and means to lock the arm to the lever and the pad to the arm in any desired positions of adjustment.

3. In a hat polishing or like machine of the class specified the combination with the rotary brushing member, of a pivoted lever, a bow-shaped arm secured at one end to said lever and having its free end located in proximity to the brushing member aforesaid, a pivoted pedal coupled by a link to the lever aforesaid for rocking the latter in a direction to move the free end of the bow-shaped arm towards and away from the brushing member, means to permit of adjustment in length of the coupling link be-

tween pedal and lever, a pressure-applying pad carried on the free end of the bow-shaped arm, means to permit of the angular adjustment of the ram in relation to the lever and of the pad in relation to the arm about a common axis which passes substantially centrally through the pad and across the arc of the arm to the point of connection between the arm and the lever, and means to lock the arm to the lever and the pad to the arm in any desired positions of angular adjustment.

4. In a hat polishing or like machine of the class specified the combination with the rotary brushing-member, of a lever pivotally mounted between its ends for rocking movement about a horizontal axis, a bow-shaped arm attached at one end to the lever aforesaid on one side of the pivot thereof and extending at its free end into proximity with the brushing-member, a pressure-applying pad carried on the aforesaid free end of the arm, a pedal operatively connected to the lever on that side of the pivot remote from the bow-shaped arm, and so weighted that the leverage exerted by the pedal and associated parts about the pivot of the lever is substantially equal to that exerted by the arm and associated parts about said pivot, and a spring arranged to resist downward movement of the pedal.

5. In a hat polishing or like machine of the class specified the combination with a

rotary brushing-member mounted for rotation about a horizontal axis, of a lever pivoted between its ends for rocking movement about a horizontal axis below that of the brushing-member, a bow-shaped arm secured at one end to the lever aforesaid on one side of the pivot thereof and extending upwardly into proximity with the brushing-member, a resilient pressure-applying pad carried on the free end of the arm, a pivoted pedal located below that end of the lever aforesaid which is remote from the bow-shaped arm and connected to said end by a link which is adjustable in length, the pedal and link being so weighted that the leverage exerted by them about the pivot of the lever is substantially equal to that exerted in the opposite direction about said pivot by the arm and its associated parts, spring means arranged to resist downward movement of the pedal, means to permit of the angular adjustment of the arm in relation to the lever aforesaid and of the pad in relation to the arm about an axis which is common to both and extends across the arc of the arm and means to lock the arm to the lever and the pad to the arm in any desired positions of adjustment.

In testimony whereof we have signed our names to this specification.

FRANK HENRY EVE.

WILLIAM JAMES WOOD.
